COMBINED TABLE AND SEAT FOR A CHILD

Leonard P. Matson, Huffman, Ala.

Application December 24, 1953, Serial No. 28,197

Term of patent 3½ years

(Cl. D33—14)

Fig. 3.

Fig. 2.

Fig. 1.

Fig. 1 is a front elevational view of the combined table and seat showing my new design;

Figs. 2 and 3 are side and rear elevational views, respectively, thereof.

I claim:

The ornamental design for a combined table and seat for a child, as shown.
